COMBINED MICROPHONE AND CONTROL HANDLE FOR DICTATING MACHINE

James I. McVay, Toronto, Ontario, Canada, assignor to
Sonograph Limited, Leaside, Ontario, Canada, a corporation

Application December 14, 1953, Serial No. 28,054

Term of patent 14 years

(Cl. D26—14)

To all whom it may concern:

Be it known that I, James I. McVay, a citizen of Canada, residing at Toronto, Ontario, Canada, have invented a new, original, and ornamental Design for a Combined Microphone and Control Handle for Dictating Machine, of which the following is a specification, reference being had to the accompanying drawing, forming part thereof.

Fig. 1 is a front view of the combined microphone and control handle for dictating machine showing my new design,

Fig. 2 is a side view thereof; and

Fig. 3 is a top view thereof.

I claim:

The ornamental design for a combined microphone and control handle for dictating machine, as shown.
